6 Sheets-Sheet 3

Technical drawing of a metal strip with various markings and labels. The strip is oriented vertically. At the top left, the text 'L D I E P I G A I N' is written above a small circle. To the right of this, the number '16' is written vertically. In the center, the numbers '30' and '32' are written vertically. To the right of '32', the numbers '34' and '31' are written vertically. At the bottom left, the number '10' is written vertically. At the bottom right, the number '11' is written vertically. The entire strip is labeled 'Fig. 4' at the top left. The drawing is enclosed in a rectangular border with a dashed line inside.

CIPHER APPARATUS

Morgan Cyprian McMahon O'Brien, Baldeck,
England, assignor to O'Brien Cipher Machines
Limited, London, England, a British company

Application May 11, 1939, Serial No. 273,120
In Great Britain June 27, 1938

11 Claims. (Cl. 35—2)

This invention relates to apparatus, for enciphering and deciphering messages, of the kind comprising a plurality of individually movable elements arranged side by side, each carrying a cipher alphabet and each movable to a plurality of different positions corresponding to the letters of a plain alphabet. When all the elements have been moved the enciphered or deciphered message is read from the cipher alphabets, a suitable reading line being provided for this purpose.

The term "alphabet" is herein used to mean the letters of the alphabet and/or the digits and/or any other symbols or characters. The term "letter" is herein used to mean any character in such an alphabet. The term "plain alphabet" means the alphabet arranged in a normal order while the term "cipher alphabet" means the alphabet arranged in any arbitrary order.

According to one aspect of the present invention, an enciphering and deciphering machine of the kind described comprises a plurality of flexible endless bands arranged side by side and settable individually each to any one of a number of positions corresponding to the letters of a plain alphabet and carrying each a pair of reciprocal cipher alphabets arranged side by side lengthwise of the band, and means providing a reading line common to all the cipher alphabets.

The pair of alphabets on each band are preferably printed in different colours, for example, one in black and the other in red, and, for convenience, one will be referred to as the black alphabet and the other as the red alphabet.

With the present arrangement a message can be enciphered by setting the bands in accordance with the letters of the message and reading either the black letters or the red letters at the reading line. The cipher message can be deciphered by setting the bands in accordance with the letters of the cipher message and reading the black letters if the message was enciphered by means of the red letters or vice versa. The machine provides thus two alternative ciphers each of which can be used to encipher a message or to decipher a message enciphered by means of the other.

By the term "reciprocal alphabets" is meant two cipher alphabets such that a letter enciphered by means of one alphabet can be deciphered by enciphering the cipher letter by means of the other alphabet.

To facilitate reading the black or the red letters at the reading line, in enciphering and deciphering, there may be provided a comb arranged to

cover the black letters only or the red letters only at the reading line and movable transversely of the bands so that either the red letters or the black letters may be visible.

According to another aspect of the present invention an enciphering and deciphering machine comprises two spaced axles, a plurality of pulleys rotatable on each axle, a plurality of bands each supported by the pulleys one on each axle, and carrying each a plain alphabet and a plurality of different cipher alphabets arranged end to end lengthwise of the band, means providing a setting line common to all the plain alphabets on the band, which setting line is so disposed that, before a band is set, the plain alphabet on that band will lie on a straight lap of the band, and a plurality of means each providing a reading line to a different one of the cipher alphabets on each band.

After setting the bands, a reading can be taken at any of the reading lines so that a message can be enciphered in any of two or more ciphers without any adjustment being made to the machine.

According to another aspect of the present invention an enciphering and deciphering machine comprises a plurality of steel or like strong tapes supported side by side, each carrying a plain alphabet and formed with a perforation or projection adjacent each letter of the plain alphabet, a member extending across all the tapes and forming a stop to limit the movement of a stylus or the equivalent engaged with a perforation or projection on one of the tapes, and two spaced hooks or clips carried by each tape in positions to engage opposite ends of a paper or like strip and hold the paper or like strip on the tape.

With this arrangement the cipher alphabet or alphabets is printed on the paper or like strip so that the cipher can be changed by replacing each strip by another. Further the tape itself can be of steel or other strong material so that it will withstand rough usage due to its being set, while the strip can be of paper, fabric or other weak material which is cheaper than the material of the tape. Thus, changing the cipher merely involves changing the relatively inexpensive strips and does not involve the changing of the more expensive tapes.

When the strips are made of paper, one of the hooks or clips is preferably movable relatively to its tape and is spring-pressed in a direction to maintain the strip in tension. When the strip is made of fabric, it may be provided with an elastic portion at one of its ends so that it

will be tensioned between the hooks or clips on its tapes.

The present invention also provides a paper sheet cut to form a plurality of strips connected together at each end by upper and lower marginal portions, perforated to form a tear-line between each marginal portion and the adjacent end of each strip and provided with holes one at each end of each strip. Each strip carries one or more cipher alphabets. The sheet is placed on the tapes of the machine just described and the holes on the strips are engaged with the hooks on the tapes. The upper and lower marginal portions are then torn off leaving each strip properly supported on its tape.

Specific embodiments of the invention will now be described with reference to the accompanying drawings, in which:

Figure 1 is a plan view of one form of the cipher machine,

Figure 2 is a section on the line 2—2 of Figure 1,

Figure 3 is a plan view of the central part of the machine showing some of the tapes in the positions they occupy when a message has been enciphered,

Figure 4 is an underplan illustrating the manner in which the second series of cipher alphabets are read,

Figure 5 shows a suitable form of paper sheet for use with the apparatus,

Figure 6 is an enlarged sectional view showing the spring-plungers for tensioning the paper strips,

Figure 7 is a view corresponding to Figure 6 but showing the plunger in the position it occupies when tension is relieved for replacing the paper strips,

Figure 8 is a section, to an enlarged scale, on the line 8—8 of Figure 1,

Figure 9 is a section, to an enlarged scale, on the line 9—9 of Figure 1,

Figure 10 is an elevation of the spring-cover,

Figure 11 is a perspective view of the complete machine in its operating position,

Figure 12 is a detail of a modification to the strip, and

Figure 13 shows an alternative form of replaceable pulleys.

As shown in Figures 1 to 10 the machine comprises two side-plates 10, 11 of synthetic resin or other suitable light material interconnected by cross-bars 12, 13, by axles 14, 15 and other cross-members described below. Each axle supports a number of pulleys 16 which are independently rotatable on the axles.

The cross-bars 12 and 13 support upper and lower grooved plates 17, 18 of synthetic resin which serve to support the tapes hereinafter described.

Passing around each aligned pair of pulleys 16 is a strong steel endless tape 19a, 19b, etc., each of which tapes, as shown in Figures 1 and 10, is printed with what is herein termed a "plain alphabet"; that is to say, the twenty-six letters of the alphabet in their normal order followed by the ten numerals in their normal order. Adjacent each of these thirty-six characters is a hole 20 for engagement by the point of a stylus, pencil or other tool whereby the steel tape may be moved endwise of its length. As shown in Figures 1 and 2 each tape carries near the beginning of the plain alphabet a metal plate 21 formed with a lug-portion 22, the purpose of which is explained hereinafter, and a hook-portion 23 for engaging

a hole in the end of a paper strip 24. At a point in its lower lap, as seen in Figure 2, each steel tape also carries a bracket 25, the two arms of which form a support for a plunger the details of which are seen in Figures 6 and 7. The plunger comprises a rod 26 carrying a flange or collar 27 which is engaged by a spring 28 the other end of which abuts against the right-hand limb of the bracket 25. The right-hand end of the plunger is turned over to form a hook 29 which passes through a slot 30 in the steel tape 19. The lower plate 18 is formed with a plurality of grooves 31 each of which accommodates the plunger-bracket 25 as shown in Figures 6, 7 and 9. The spring 28 ordinarily maintains the paper-strip 24 in tension as shown in Figure 6. The manner in which this tension is automatically relieved will be explained below with reference to the operation of the machine.

Referring to Figures 1 and 2, it will be seen that the side-plates 10 and 11 are additionally braced by means of a cross-bar 32 which also constitutes a rearward abutment for a flat metal plate 33 which is slidable in grooves 34, 35, in the side-plates 10 and 11 respectively. The metal plate 33 has an upstanding front ledge 36 for engagement by the fingers of an operator and for co-operating with the lugs 22 of the plates 21. It also carries a wire releasing shaft 35 having a central handle-portion as shown, journal-portions 36 to engage with bearings 37 formed on the plate 33, and teeth 38 which project down through holes in the plate (Figure 9) to co-operate, in a manner hereinafter described, with depressions 39, 40 formed in the marginal portions of the top plate 17. The teeth 38 are continuously pressed downwardly by springs 70 each of which is anchored at one end to the wire shaft 35 and at the other end is turned over as shown at 71 to rest on the plate 33.

The machine so far described is covered as to part of its upper surface and substantially the whole of its lower surface by means of the spring cover shown in Figure 10. This comprises a long lower limb 41 which lies underneath the machine with its left-hand end resting on a metal plate 42 (Figure 2) secured to the side-plates 10 and 11, and a short upper limb 43 which overlies the right-hand end of the upper surface of the machine. The cover is located against endwise movement by downward protuberances 44 which engage co-operating depressions in the side-plates 10 and 11; the resiliency of the cover causes these protuberances to snap into position when the cover is pushed home. The cover is located against lateral movement by engaging rebates 45, 46, (Figures 8 and 9) formed in the side-plates 10, 11, respectively. At the end of its shorter and upper limb the cover 43 carries a sliding channel-shaped plate 47 by means of 60 studs 48 on the plate which engage elongated holes 49 in the cover. The plate 47 carries forwardly-projecting comb-like wire teeth 50 which co-operate with the characters of the cipher alphabets on the paper strips in a manner described below. The plate 47 also carries an upwardly-projecting pin 51 which passes through an elongated hole 52 in the cover whereby the plate may be shifted from one position in which the teeth 50 obscure the characters in the right-hand cipher alphabets to another position in which they obscure the characters in the left-hand cipher alphabets. The cover is also formed with a hole 53 and the bottom of the plate 47 beneath this hole is suitably coloured, for example, by black and red spots, so that the posi-

tion to which the comb has been moved may be seen at a glance by inspecting the colour visible through the hole 53.

As shown in Figure 4, the cover 43 is formed on its underside with a rectangular reading aperture 54 through which the characters on the paper tapes are visible. Adjacent the aperture 54 the cover carries a channelled plate 55 (Figure 10), similar to the plate 47, having comb-like teeth 56 similar to the teeth 50 projecting into a position in which they are visible through the aperture 54 when the machine is turned upside-down. The plate 55 has an operating pin 57 and may be mounted in the same manner as the plate 47. The cover may be similarly formed with a hole like the hole 53 for the purpose of indicating at a glance the position to which the comb has been moved.

Each of the paper strips 24 carries four cipher alphabets, each of thirty-six characters, in two pairs. When the steel tapes are in their initial or zero positions, as shown in Figure 11, the first pair of alphabets extends from a point just beyond the teeth 50, around the pulleys on the axle 15, to a point in advance of the reading aperture 54. The second pair extends from just beyond the aperture 54 to a point near the hooks 29. Each pair of cipher alphabets comprises two sets of characters which, though arbitrarily arranged, are related each to the other in such manner that if a character dialled on the steel tape gives a certain cipher character on one set, that cipher character dialled on the steel tape will give the original character on the other set. For example, if the steel tape 19a is moved until the letter "C" lies adjacent the edge of the metal plate 33, the character "7" appears adjacent the first comb-tooth 50 as shown in Figure 3; if the comb is now moved to its other position by means of the pin 51, and the steel tape 19a moved to a position in which the character "7" lies adjacent the edge of the plate 33, the letter "C" will appear adjacent the tooth 50. The two sets of characters in the second pair of cipher alphabets are reciprocal in like manner.

The two pairs of cipher alphabets are spaced apart endwise of the paper strips so as to leave a gap of the height of one character. Such a gap is shown as 86 in Figure 12. Thus, when the steel tapes are in their zero positions, none of the cipher-characters is visible on any of the paper strips, either at the comb 50 or the aperture 54.

It will be understood that the cipher alphabets are normally different for each paper strip.

Remaining details of construction of the machine will appear from the description, which now follows, of the manner in which the machine is operated.

The machine is laid on a table or other suitable support with its left-hand end (referring to Figure 1) towards the operator and its right-hand end away from him. Let it be assumed that the message to be enciphered begins with the word "Chicago." The operator first decides which of the ciphers he is going to use, that is to say, whether he will use the cipher alphabets extending from the comb 50 to the comb 56 or the cipher alphabets extending from the comb 56 to the plungers 25. Assuming that the first of these ciphers is to be used, he sets the comb 50 in the appropriate position for enciphering by operating the pin 51. For example, the arrangement may be such that, for enciphering, the hole

53 shows the colour black and the wire teeth 50 obscure the right-hand column of letters on the paper strips and, for deciphering, the hole 53 shows the colour red and the teeth 50 obscure the left-hand characters. As shown in Figure 11, the operator first inserts the point of a stylus or pencil into the hole 20 in the steel tape 19a opposite the letter "C" and draws the pencil towards him until its movement is arrested either by the forward edge of the plate 33 or, preferably, by the forward edge of a fixed reading plate 60 shown in Figures 1 and 2. During this movement the point of the stylus or pencil is accommodated beneath the steel tape by a groove 61a, formed in the upper plate 17 (Figure 8), a similar groove 61b, 61c etc. being provided beneath each of the other tapes 19b, 19c etc. During the operation of drawing the stylus towards him, the operator directs his attention to the next steel tape 19b and looks for the letter "H" so that he need not look at the first tape 19a again. When the movement of the first tape is arrested by the plate 60 he removes the stylus and inserts it in the hole opposite the letter "H" in the second tape 19b. The first seven tapes are thus all moved until they occupy the positions shown in Figure 3. The remaining tapes are, of course, moved according to the remaining thirteen of the first twenty letters of the message but the present description deals, for the sake of simplicity, with only the first seven letters. When all the twenty tapes, as shown, have been moved in this way the plain-language message will have been set up along the edge of the reading plate 60 as shown in Figure 3. By reading along this line the operator can immediately detect and correct any errors of operation which may have occurred.

The operator now reads the cipher letters between the teeth 50, that is to say, the twenty letters, the first seven of which are 7VV85FX. This cryptogram is written down and the steel tapes are now all returned to their initial neutral positions by pressing forwardly on the ledge 84 of the sliding plate 33. The forward edge of this plate engages during its travel with the lugs 22 of the plates 21 whereby all the steel tapes are restored. Movement of the sliding plate 33 is limited, however, by the automatic engagement of the teeth 38 with the foremost depressions 39 in the top plate 17. The plate 33 is now returned to the position shown in Figures 1 and 11 its return movement being limited by the cross-bar 32, and the next twenty characters of the message are enciphered and checked, and the cryptogram written down as before. The operation of the machine continues in this way until the entire message has been enciphered.

It will now be supposed that a correspondent, having an exactly similar machine with exactly similar paper strips, receives the cryptogram and wishes to decipher it. He proceeds in exactly the same way and, to make this clear, reference will be made to the first seven letters of the received message. The deciphering operation is performed with the comb 50 in the position in which it obscures the left-hand end cipher characters and exposes the right-hand end characters. With the parts in the position shown in Figure 11, the operator takes his stylus, inserts the point in the hole 20 adjacent the character "7" in the steel tape 19a and slides the steel tape along until the movement of the stylus is arrested by the reading bar 60. He then proceeds to set up the characters VV85FX on the

succeeding six tapes until the cryptogram appears along the reading bar 60 where it can be checked with the received message. When the tapes are set up in the manner above described, the message will appear between the teeth 50, 5 beginning with the word "Chicago."

As has already been explained each paper strip 24 carries two pairs of cipher alphabets end to end, the alphabets of each pair being reciprocal alphabets as above defined. Thus the machine contains two complete ranges of cipher for each set of paper strips used. It is intended that the range of cipher shall be changed at frequent intervals and one change can be made by using the cryptogram appearing at the aperture 54 instead of that appearing between the teeth 50. For example, instead of transmitting the cryptogram 7VV85FX the first operator could have sent the cryptogram LOEPGAN. This message, when received, would have been deciphered by shifting the plate 55 into its other position, moving the steel tapes according to the cryptogram, and reading the plain-language message at the aperture 54.

However, the paper strips may be completely renewed in a simple manner as follows. The spring-cover 43 is removed by means of a suitable knob 72. The metal plate 33 is now slid forwardly until the teeth 38 engage the notches 39. At this point the steel tapes are all in their neutral positions as has been explained above. The operator now lifts the handle-portion 85 of the wire-shaft whereby the teeth 38 become disengaged from the notches 39 and further forward movement is possible. The plate 33 is pressed forwardly whereby all the lugs 22 of the plates 21 are pressed to the right as shown in Figure 2. However, the plungers 26 are incapable of moving further to the left because of their engagement with the ends 73 of the grooves 31 in the bottom plate 18, so that the result of such additional movement is to compress the springs 28 whereby all the plungers 26 move into the position illustrated in Figure 7. Tension on the paper strips is thus relieved whereby the strips can readily be removed from the hooks 23 and 29 and destroyed.

The simplest manner of replacing the strips is to use a sheet of paper as shown in Figure 5 in which the individual strips 24 are connected together at each end by lateral strips 74. The sheet thus formed is provided with perforations 75 forming tear lines at the junction of each strip 74 with the strips 24. The entire sheet is placed in position on the machine by engaging the holes 76 with the hooks 23, wrapping the sheet around the pulleys of the axle 15 and engaging the holes 77 with the spring-pressed hooks 29 on the underside of the machine. The sliding plate 33 is now withdrawn to the position in which the teeth 38 engage the first notches 39; thus the sheet of paper is tensioned by the springs 28. The two strips 74 are now torn off and the strips 24 are thus independent of one another and individually movable. The metal cover 43 is now replaced and the machine is ready for use.

In an alternative form of the invention, the strips of paper may be stored separately and suitably numbered so that they may be applied separately and in the proper order to the steel tapes.

While it is desirable that the cipher alphabets should be readily replaceable in the manner above referred to where great secrecy is neces-

sary, it is possible to obtain a useful cipher of less secrecy by printing the cipher alphabets on the steel tapes in the manner of the plain alphabets. It will be understood that, with such an arrangement, it is necessary to renew the steel tapes 19 in order to change the cipher range.

In the third possibility, the removable strips, instead of being of paper, may be of fabric as shown in Figure 12. The strip 24 is formed with eyelets 78 one at each end for engagement by the hooks on the steel tape. It is possible to dispense with the plunger-mechanism of Figures 6 and 7 by providing each strip 24 with an elastic portion 79 to facilitate its application to and removal from the steel tape. By the use of fabric strips as shown in Figure 12 the same strips can be used for a long period, or can be brought back into use after having been temporarily discarded.

The pulleys 16 are preferably of light metal such as aluminium alloy and, according to a preferred form of the invention, may be separated from one another by steel washers 80 as shown in Figure 13. The steel washers serve the purpose of locating the pulleys in their correct position along the axles 14 and 15 and also of locating the steel tapes 19.

The spring-cover shown in Figure 10 has the advantage that it enables the strips bearing the cipher alphabets to be readily replaced. No threading of the strips beneath reading lines or other obstructions is necessary as it would be if the combs 50 and 56 were fixedly carried by the side-plates 10 and 11. Moreover, the underpart 41 of the cover protects the strips bearing the cipher alphabets during operation of the machine so that, if the machine is resting upon an uneven surface, the paper strips are free to move without risk of being torn.

It will be seen that the complete machine is of very small overall dimensions, the exact size depending on the necessary size of the individual characters used on the metal tapes and the paper strips and upon the number of steel tapes required. In the example described with reference to the drawings, the machine has twenty steel tapes, each carrying a paper strip and this number, where the cipher range is changed from time to time, is found to give a cipher of great subtlety. However, it would be possible in some circumstances to use a smaller number of tapes and it might be advisable, in other circumstances, to use a larger number. It will be understood that there is no limit to the number of tapes which could be employed and, where it is not necessary for the machine to be readily portable, a very much larger number would be used.

It will be seen that, for all operative positions of the steel tapes, the character to be dialled lies on a straight lap of the steel tape and the corresponding characters of the cipher alphabets also lie on a straight lap. By this arrangement the selection of the appropriate hole 20 for the insertion of the stylus, and the reading of the cipher characters, is greatly facilitated.

In the machine above described the alphabets on the paper strips are reciprocal alphabets in order that the same machine and same paper strips may be used both for enciphering a message and deciphering the resulting cryptogram. In an alternative form of the invention, however, the cipher alphabets need not be reciprocal alphabets but a different machine would then have to be used for deciphering from the machine used for enciphering.

Enciphering and deciphering can be performed

very rapidly with a machine according to the invention. In one method of working, two or more machines may be used the paper strips of which may be identical or, preferably, different so as to increase the subtlety of the cipher. Two operators are employed. Number one takes the first machine, enciphers the message, and checks the cryptogram. He hands this machine to number two who types the cryptogram and transmits it; meanwhile number one proceeds to encipher the next batch of letters by means of the second machine. A similar procedure may be adopted for deciphering.

I claim:

1. An enciphering and deciphering machine comprising a plurality of flexible bands arranged side by side and settable individually each to any one of a number of positions equal to the number of characters in a plain alphabet and allocated respectively and consecutively to said characters, said bands carrying each a pair of reciprocal cipher alphabets arranged side by side lengthwise of the band.

2. An enciphering and deciphering machine comprising two spaced axles, a plurality of pulleys rotatable on each axle, a plurality of tapes each supported by one of the pulleys on each axle and carrying a plain alphabet and a plurality of different cipher alphabets arranged end-to-end lengthwise of the tape, a plate extending across said tapes whereof the edge constitutes a reading line common to all the plain alphabets which reading line is spaced from one of the pulleys at a distance greater than the length of tape occupied by the plain alphabet so that, before a tape is set, the plain alphabet on that tape will lie on a straight lap of the tape, a cover extending across said tapes and a plurality of apertures therein constituting a reading line to each different one of the cipher alphabets.

3. Apparatus of the kind described comprises two spaced axles, a plurality of pulleys rotatable on each axle, a plurality of tapes each supported by two of said pulleys, one on each axle, each tape carrying a plain alphabet and a plurality of different cipher alphabets arranged end-to-end lengthwise of the tapes.

4. An enciphering and deciphering machine comprising a plurality of steel or like strong tapes supported side by side, each movable in the direction of its length, each carrying a plain alphabet and each formed with a perforation or projection adjacent each character of the plain alphabet, a member extending across all the tapes and forming a stop to limit the movement of a stylus engaged with a perforation or projection on one of the tapes, and two spaced hooks carried by each tape to engage opposite ends of a paper or like strip and hold the said strip on the tape.

5. Enciphering and deciphering apparatus comprising a plurality of endless bands supported side by side, each carrying a plain alphabet and formed with perforations adjacent the characters of the said alphabet, a member extending across the bands to limit the movement of an implement engaged with one of said perforations, two spaced hooks carried by each tape to engage opposite ends of a paper strip, and means for spring-pressing one or both of said hooks in such direction as to maintain said paper strips in tension.

6. Cipher apparatus comprising a plurality of endless bands arranged side by side, two hooks

carried by each band to support a strip of paper between them, a plunger carrying one of said hooks and spring-pressed in a direction to tension the paper strip, a frame-member constituting an abutment for said plunger whereby movement of the band beyond a limiting position relieves said tension whereby the paper strip may be removed and replaced.

7. In a cipher apparatus, an endless metal tape, hooks spaced apart lengthwise of the tape to support a paper strip between them and means acting upon one hook to press it resiliently away from the other and so maintain the paper strip in tension.

8. Cipher apparatus comprising a plurality of strips arranged side by side and individually and successively movable in accordance with the characters of a message to be enciphered or of a cryptogram to be deciphered, a pair of reciprocal cipher alphabets side by side on each strip one on the right-hand side and the other on the left-hand side thereof, and an adjustable comb having a series of teeth adapted to obscure wholly or partly either the right-hand cipher characters of all the strips or the left-hand characters, in a certain reading position, according to the position of adjustment of the comb.

9. Apparatus for enciphering and deciphering messages comprising a pair of spaced axles, side-plates carrying the ends of said axles, a plurality of pulleys on each axle, a plurality of endless metal bands each passing around two pulleys, one on each axle, a plurality of apertures in each band, a stylus engageable with said apertures for selectively driving the bands around the axles, means for mechanically arresting movement of the stylus and therefore of the band with which it engages, a plurality of lugs, one on each band, a sliding plate engaging said side-plates and adapted to engage with all of said lugs to return the bands all to a zero position, and means to limit the returning movement of said bands.

10. Apparatus as claimed in claim 9, wherein said limiting means comprises a notch in each side-plate and a pair of spring-pressed teeth carried by the sliding plate and adapted to engage with said notches.

11. Apparatus as claimed in claim 9 comprising, in addition, two spaced hooks for engaging and supporting a strip of less robust material, one said hook being carried on the same straight lap of the band as that against which the said arresting means lies, and the second hook being carried on the other straight lap, a plunger associated with the said second hook, a spring normally operative to press the said plunger, and therefore the said second hook, in a direction to maintain said strip in tension, a fixed abutment for co-operation with said plunger, a notch in each said side-plate, a pair of spring-pressed teeth carried by the sliding plate and adapted to engage with said notches when the bands are returned to their zero positions by engagement of said sliding plate with said lugs, a second pair of notches in said side-plates, and means for releasing said teeth from the first said notches whereby the sliding plate may be pressed into a position in which the teeth engage the second notches, the plungers are all arrested by their engagement with the abutments and the distance between the two hooks on each band is thus reduced, for the purpose of renewing the said strips.
